UNITED STATES PATENT OFFICE.

MARVIN S. WEAVER, OF JOHNSON CITY, TENNESSEE.

FIBER-TRIMMING APPARATUS.

1,139,609.

Specification of Letters Patent. Patented May 18, 1915.

Application filed September 8, 1911, Serial No. 648,368. Renewed February 5, 1915. Serial No. 6,372.

To all whom it may concern:

Be it known that I, MARVIN S. WEAVER, a citizen of the United States, residing at Johnson City, in the county of Washington and State of Tennessee, have invented a new and useful Improvement in Fiber-Trimming Apparatus, of which the following is a specification, reference being had to the accompanying drawing.

10 My improvement relates to means for removing loose fiber ends from the surfaces of fiber fabrics, for example, cloth, carpets, etc.

The object of the improvement is to provide means for placing the loose fiber ends, 15 which are to be removed wholly or in part, approximately perpendicular to the surface to which they are attached, in order that said fiber ends may be more readily reached or engaged by the means used for removing 20 or partially removing such fiber ends. For example, in the finishing of cloth by shearing or singeing the surface, the fiber ends which are to be removed by shearing or singeing are to be made to stand approximately 25 perpendicular to the surface of the cloth, in order that they may be more readily engaged or reached by the means used for shearing or singeing. Moving air is the agent used for causing such fiber ends to 30 stand approximately erect or perpendicular to the surface to which said fibers are attached. As will hereinafter appear, the air thus used may be moved by driving or by 35 suction or exhaustion; and the means used for producing the air movement may be varied according to conditions. The mechanism used for producing such air movement may also, as will hereinafter appear, be used 40 as a means for conveying or conducting the cut portions of the fibers away from the surface.

In the accompanying drawings, Figure 1 is a sectional elevation of an apparatus embodying my improvement; Fig. 2 is a sectional elevation of the same apparatus looking at right angles to the direction of sight in Fig. 1; Fig. 3 is an upright section of another form of the apparatus; Fig. 4 is a sectional plan of the same apparatus; Fig. 5 is a modification of the apparatus shown in Figs. 3 and 4; Fig. 6 is a modification of the apparatus shown in Figs. 1 and 2.

Referring first to Figs. 1 and 2, A is a sheet of cloth or similar fiber fabric from 55 the surface of which projecting fiber ends

are to be sheared. A stationary knife, 1, is supported by a plate, 2, by means of binding bolts, 3, extending through slots, 4, in the plate, 2. Any number of adjusting bolts, 5, are seated in the plate, 2, to bear against the back of the knife, 1, for the adjustment of 60 said knife. Three spiral blades, 6, are arranged to work in opposition to the blade, 1, for shearing. Said blades are mounted on the arms, 7, supported on hubs, 8, which 65 surround and are rigidly secured to a rotary drive shaft, 9, resting in suitable bearings (not shown) and receiving power by any means not shown. Directly below the cutting edge of the knife, 1, is a pneumatic head, 11, having a mouth, 12, next said edge. Said head is a little longer than said knife, and said mouth is narrow and approximately as long as said knife. The sheet of 70 cloth extends across and rests upon the lips, 13, the space between said lips and the knife, 1, being made sufficient only for the free movement of the cloth between said lips and the cutting edge of said knife. At each 75 side of and parallel to the pneumatic head 80 is a guide roller, 14, beneath which the sheet of cloth passes. The sheet of cloth extends to winding or drawing apparatus (not shown) located rightward of the righthand guide roller, 14. Said winding or drawing 85 apparatus may be of any well known form and operated at suitable speed for drawing the cloth rightward between the stationary knife, 1, and the pneumatic head, 11, while the shaft, 9, bearing the spiral blades, 6, is 90 being rotated. A pipe, 15, leads to the pneumatic head, 11, from any suitable devices or apparatus for driving air through 95 said pipe and thence through said pneumatic head and the mouth, 12, against and through the cloth sheet, A. The stream of air thus moving through said cloth is approximately perpendicular to the surface of said cloth and serves to raise all free fiber ends approximately perpendicular to said 100 surface while said fibers approach the cutting edge of the stationary knife, 1. Causing said fibers to thus stand approximately perpendicular to said surface adapts them to be engaged between the stationary knife 105 and the then approaching spiral blade for shearing, such shearing being approximately perpendicular to the path traversed by the fabric.

In Figs. 3 and 4, a stationary sickle blade, 110

16, is substituted for the stationary knife, 1, of Figs. 1 and 2 and the reciprocatory blade, 17, is substituted for the spiral blade, 6. A pitman, 18, reciprocates the blade, 17. 5 The cloth, A, extends over a roller, 19, and a guide plate, 20. Above the sickle blades and the cloth is a hood or housing, 21, forming a pneumatic head. A pipe, 22, leads from said head to any suitable means or 10 mechanism for exhausting air out of said head through said pipe. The hood, 21, projects forward of the sickle blades and bears upon the upper face of the cloth, A, thus leaving a space between the edge of said 15 hood and the knives along which only the cloth intervenes between the outside atmosphere and the space within the pneumatic hood, thus allowing the outside air to push upward through the cloth in a stream 20 to supply the air being exhausted from said head through the pipe, 22. This stream of air thus passing by exhaustion upward through the cloth adjacent the cutting means (the two sickle blades), causes the 25 loose fiber ends on the upper face of the cloth to rise and stand approximately perpendicular to the upper face of the cloth in front of said cutting means, in suitable position to be sheared closely to the surface of 30 the cloth.

In Fig. 5, the sickle blades are used as in Figs. 3 and 4; but the hood, 21, is omitted and the pneumatic head, 11, of Figs. 1 and 2 is located below the cloth for driving air 35 upward through the cloth in front of the sickle blades.

In Fig. 6, the cutting mechanism of Figs. 1 and 2 is used; but the pneumatic head, 11, of Figs. 1 and 2 is omitted and a pneumatic 40 head, 23, placed above the knife, 1, and the knife plate, 2, and around the rotary knife member which comprises the three spiral blades, 6, the wall of the head, 23, meeting the upper face of the cloth a little way in 45 front of the cutting edge of the stationary knife, 1, thus leaving a portion of the cloth immediately in front of the cutting edge of said knife clear for the passage of air upward through the cloth into the pneumatic 50 head. Air is exhausted through a port, 24, opening from said pneumatic head. Two guide bars, 25, are located parallel to the cutting edge of the knife, 1, and form guides for the sheet of cloth passing between said bars and said knife. During the 55 exhaustion of air through the port, 24, air passes upward through the cloth in front of the knife, 1, in a stream which is approximately perpendicular to the surface of the 60 cloth and causes the loose ends of fibers on the upper face of the cloth surface to rise and stand approximately perpendicular to the surface of the cloth in suitable position to adapt the knives to shear said fibers close 65 to the surface of the cloth.

In all of these several forms of the apparatus, there is a relative movement or traversing between the fiber-removing means and the fiber-bearing surface; and the cutting is done in a plane which is parallel to 70 the fiber-bearing surface or the fabric path; and the air movement is approximately perpendicular to the fiber-bearing surface or fabric path and away from said surface or fabric path and adjacent to the fiber-removing means. In Figs. 1, 2 and 5, the stream of air thus moving approximately perpendicularly away from the fiber-bearing surface is formed by driving air to and through the fabric having the fiber-bearing surface, 80 while in the forms illustrated by Figs. 3, 4 and 6, such stream of air is formed by exhaustion or the production of a partial vacuum above the fiber-bearing surface.

The spiral blades, 6; the arms, 7, the hubs, 85 8, and the rotary drive shaft, 9, of Figs. 1, 2 and 6 together constitute a rotary cutting member operating in conjunction with the stationary knife, 1, to shear said fibers.

In the forms shown by Figs. 3, 4 and 6, 90 the fiber fragments cut from the cloth are carried away with the air exhausted from the pneumatic head.

The method herein described is made the subject of an application for Letters-Patent, 95 Ser. No. 748,969 filed Feb. 17, 1913.

I claim as my invention:

1. An apparatus adapted to relatively traverse the surface of a sheet form fiber fabric and comprising means operating parallel 100 to said surface for removing surface fiber ends along said surface and means for moving air and limiting such movement to a course through said fabric and adjacent and toward said fiber end removing means, 105 whereby surface fiber ends may be directed outward from said surface into position to be removed by the fiber end removing means, substantially as described.

2. An apparatus adapted to relatively traverse the surface of a sheet form fiber fabric and comprising means operating parallel to the fabric for cutting surface fiber ends along said surface and means for moving air and limiting such movement to 115 a course through said fabric and adjacent and toward said fiber end removing means, whereby surface fiber ends may be directed outward from said surface into position to be cut by the cutting means, substantially as described.

3. An apparatus adapted to relatively traverse the surface of a sheet form fiber fabric and comprising means operating parallel 125 to said surface for removing surface fiber ends along said surface and means for moving air by exhaustion and limiting such movement to a course through said fabric and adjacent and toward said fiber end removing means, whereby surface fiber ends 130

may be directed outward from said surface into position to be removed by the fiber end removing means, substantially as described.

4. An apparatus adapted to relatively traverse a sheet form fiber surface and comprising means operating parallel to the fabric for cutting surface fiber ends along said surface, and means for moving air by exhaustion and limiting such movement to a course through said fabric and adjacent and toward said fiber end removing means, whereby surface fiber ends may be directed outward from said surface into position to be cut by the cutting means, substantially as described.

5. An apparatus adapted to relatively traverse a sheet of fiber fabric and comprising surface fiber end cutting means located opposite and near said surface and outside of the plane of said fabric and consisting of a relatively stationary knife and a relatively movable knife set for cutting parallel to the plane of the fabric, and said apparatus also comprising means for moving air and limiting such movement to a course through said fabric and adjacent and toward said knives, whereby such fiber ends may be directed outward from said surface into position to be cut by said knives, substantially as described.

6. An apparatus adapted to relatively traverse the surface of a sheet form fiber fabric and comprising surface fiber end cutting means located opposite and near said surface and outside of the plane of said surface and consisting of a relatively stationary knife and a relatively movable knife for cutting parallel to the plane of the fabric, and said apparatus also comprising means for moving air by exhaustion and limiting such movement to a course through said fabric and adjacent and toward said knives, whereby surface fiber ends may be directed outward from said surface into position to be cut off by said knife, substantially as described.

7. An apparatus adapted to relatively

traverse a sheet form fiber fabric and comprising surface fiber end cutting means located opposite and near said fabric and outside the plane of said fabric and consisting of a relatively stationary knife and a rotary cutting member for cutting parallel to said fabric, and said apparatus also comprising means for moving air and limiting such movement to a course through said fabric and adjacent and toward said cutting mechanism, whereby fiber ends may be directed outward from said surface into position to be removed by said cutting means, substantially as described.

8. An apparatus having a path for a sheet form body and comprising fiber end removing means outside of and beside said path and operating parallel to said path and means for moving air and limiting such movement to a course through said path opposite and toward said fiber end removing means, whereby fiber ends on a sheet form fiber fabric body in said path may be directed outward into position to be operated upon by the fiber end removing means, substantially as described.

9. An apparatus having a path for a sheet form body and comprising fiber end cutting means located outside of and beside said path and operating parallel to said path and means for moving air and limiting such movement to a course through said path opposite and toward said fiber end cutting means, whereby fiber ends on a sheet form fiber fabric body in said path may be directed outward into position to be operated upon by the fiber end cutting means, substantially as described.

In testimony whereof I have signed my name, in presence of two witnesses, this fifth day of September, in the year one thousand nine hundred and eleven.

MARVIN S. WEAVER.
